UNITED STATES PATENT OFFICE.

JOSEPH N. PEW, OF PITTSBURG, PENNSYLVANIA,

NATURAL-GAS CONDUCTOR.

SPECIFICATION forming part of Letters Patent No. 321,637, dated July 7, 1885.

Application filed February 24, 1885. (No model.)

To all whom it may concern:

Be it known that I, JOSEPH N. PEW, of Pittsburgh, in the county of Allegheny and State of Pennsylvania, have invented a new 5 and useful Improvement in Natural-Gas Conductors; and I do hereby declare the following to be a full, clear, and exact description thereof.

Serious difficulty has been experienced in the 10 conduction and distribution of natural gas, owing to the low temperature and high pressure at which it comes from the wells. The temperature is about 42° Fahrenheit, and the pressure in the neighborhood of two hundred 15 pounds to the square inch. The effect of the low temperature is to contract the pipes, and where they are exposed to the temperature of the atmosphere, if the latter be higher, an expansion will take place, so that there is a constant 20 expansion and contraction going on in the pipes, which tend to loosen the joints and cause them to leak. This leakage, owing to the highly explosive and extremely dangerous nature of the gas, is a very serious detriment. As the escape of the gas has been the 25 cause of many serious explosions involving destruction of property and loss of life, attempts have been made to obviate the contraction and expansion of the pipes by burying them deep enough in the ground to be below 30 the effect of the changes of temperature at the surface, the theory being that the pipes would then remain at the temperature of the gas at all times; but I have discovered that changes 35 in the temperature are caused by the reduction of pressure in the pipes, owing to the greater or less demands upon them by the users of the gas, and that to maintain them at a uniform temperature it is necessary that the pressure also remains uniform. This is impossible, owing to the fact that during the 40 day-time there is usually a much greater demand than during the night, and as the pipes are drawn on and the gas therein is more or less exhausted and reduced in pressure its expansion 45 therein produces a reduction of temperature, which causes a constant expansion and contraction of the pipes, however deep they may be buried. It has been customary 50 to lay these pipes through the streets below

the water and gas mains and service-pipes, so that leakage therefrom in ascending through the ground encounters the water and gas service-pipes which lead into the cellars and basements of buildings. There is always more or less space around a service-pipe, and the gas encountering them will follow such pipes, passing along these spaces, and enters the cellars and basements of buildings and collects there, and in many cases explodes with disastrous results.

Various provisions have been made for the purpose of carrying off the leakage from natural-gas mains, and stand-pipes leading up from a box or a layer of gravel or broken stone surrounding each joint and discharging the same in the open air have been used. These things, however, have not proven to be entirely efficacious, as more or less leakage will seek the channels before mentioned around the service-pipes and enter adjacent buildings. Where the gas-pipes are situate above the surface of the ground much of the danger of explosion is averted; but this is impracticable in the streets of towns and cities.

The object of my improvement is to increase the safety of the conduction and distribution of natural gas; and, broadly stated, it consists in laying the pipes in a suitable trench at the surface of the ground, and above the water, illuminating-gas, and other distributing pipes, which trench is covered throughout its entire length by a ventilating-cap provided with slots or holes for permitting the escape of the leakage gas into the open air, where, having no opportunity to collect, it is practically harmless. I prefer to provide my mains and pipes with expansion-joints, which will permit of the expansion and contraction of the pipes without danger of disrupting any part and causing a leak.

To enable others skilled in the art to make and use my invention, I will now describe it by reference to the accompanying drawings, in which—

Figure 1 is a longitudinal section of the trench, showing the pipe and the means of supporting the same therein. Fig. 2 is a cross-section on the line *x x* of Fig. 1.

Like letters of reference indicate like parts.

I form a shallow trench, *a*, in the bottom of which, at suitable intervals—say about eight feet apart—I lay cross-timbers *b*, of hard wood, such as oak or other suitable material. 5 The sides of the trench are lined with timbers *c*, which preferably break joint with each other, so as to make a stronger structure, and on top of said timbers are cross-timbers *d*. The timbers *b* and *d* and the intermediate 10 side timbers, *c*, are fastened together by vertical bolts *e*. On top of or between the timbers *d*, I lay a suitable flooring of boards or iron casings, *f*, which may be on a level with the surface of the street or slightly below the same, 15 so as to permit the top to be paved over like the rest of the street. In the top *f* is a continuous line of holes or vent-openings, *g*, which are designed to permit the escape of the leakage gas from the trench. In case the top is 20 paved over provision should be made for leaving these openings free, which may be done by making them through a raised rib or a series of short tubes, *g'*, which will come up flush with the surface of the pavement. In ordinary 25 weather there will be no difficulty in keeping the openings *g* clear, and if in the winter they should become clogged with ice, snow, or dirt, they can be opened by the insertion of a pick or other pointed instrument. The trench *a* 30 can be drained of water at suitable intervals by pipes or conduits leading to the proper place of discharge, and, if desired, steam or heated air may be blown through the trench by any known or suitable arrangement for that 35 purpose, not necessary here to be described. The gas-pipes *h* are laid in the trench, being supported in proper alignment by supports *b'* on the cross-timbers *b*, and the sides are of sufficient height to bring the upper cross-timbers, *d*, above the top of the pipes. As stated, 40 I prefer to provide the pipe *h* with expansion-joints.

I do not limit myself or claim the construction of any particular form of expansion-joint 45 in this case, but design to use any of the known forms suitable to the purpose, one of which is shown at *i* in Fig. 1.

While I have described and hereinafter claim a preferred form for the construction of 50 the pipe-casing inside of the trench, I do not limit myself to such construction in the use of the features forming the subject-matter of other claims.

My improvement provides for the safe and 55 perfect carrying off of the leakage gas and affords an easy access to the pipes for repairs. It gives a cheap and efficient manner of laying the pipes, and obviates all danger of interfering with or injuring the mains and serv-

ice-pipes of other systems of distribution 60 which may be laid in the streets.

As has been shown, it is impossible to prevent the expansion and contraction of the pipes, and I therefore prefer to adopt such means as will obviate danger to the joints from 65 this cause.

Owing to the conduit being at or near the surface, and yet protected by being situate below the level of the street, interference with travel and danger of breakage is averted, and 70 at the same time, owing to the continuous vents, the gas is not allowed to accumulate in a confined space, so as to lead to the danger of explosions.

I am aware that an outer casing situate 75 around the gas-main and having at intervals ventilating-pipes is not new. I am also aware that such casings formed of wood have been employed in connection with telegraph-wires, and I do not desire to claim, broadly, any of 80 these features, as the important features of my invention are a conduit for gas-pipes, said conduit having continuous vents and situate at but below the level of the surface of the ground, so as to enable the escaping gas to 85 have free access to the open air, and thereby obviate the danger of the gas collecting and passing through an inclosed space. These 90 vents should be within a short distance of each other, evenly distributed throughout the length 95 of the casing, and so numerous that one or more shall be located within a few inches of the point in the case nearest each pipe-joint, so that no opportunity shall be afforded for the collection of escaping gas.

What I claim as my invention, and desire to 95 secure by Letters Patent, is—

1. An improvement in the art of conducting and distributing natural gas, which consists in a gas pipe or main placed in a case or trench 100 at or immediately below the surface, which trench is vented continuously throughout its length, substantially as and for the purposes described.

2. A natural-gas pipe, case, or trench at or 105 immediately below the surface, having its sides lined with strong timbers connected by top and bottom cross-timbers and provided with a continuously-vented surface-cover, in combination with a gas-pipe, substantially as and for 110 the purposes described.

In testimony whereof I have hereunto set my hand this 10th day of February, A. D. 1885.

JOSEPH N. PEW.
